UNITED STATES PATENT OFFICE

FRED T. KERN, OF MILWAUKEE, WISCONSIN

CAR PULLER

Application filed August 30, 1929. Serial No. 389,373.

This invention relates to a car puller or power operated machine for shifting railway cars or the like alongside tracks or in railway yards. The invention may be used 5 to advantage in gravel plants or in any other industrial projects where it is desirable to shift railway cars relative to bins or other loading points as, for instance, in bringing empty cars to the point of loading 10 and moving them out of the way after they have been loaded and before they are made up into a train or picked up for shipment.

One of the principal objects of the present invention is to provide a car puller of this 15 character which is of simple, durable and compact construction, which operates smoothly and minimizes noise and vibration, which is easily reversible and which drives its drums either forwardly or reversely at 20 variable speed and power ratios whereby empty cars may be moved at a rapid rate or at high speed when desirable and yet ample power at a slow speed is available for shifting loaded cars or for pulling a number of 25 cars up grade.

Other objects and advantages reside in certain novel features of the construction, arrangement and combination of parts which will be hereinafter more fully described and particularly pointed out in the 30 appended claims, reference being had to the accompanying drawings, forming a part of this specification, and in which:

Figure 1 is a plan view of a car puller 35 embodying the present invention, the guard casings for the gearing and other parts being omitted for the sake of illustration;

Figure 2 is a view in end elevation looking 40 toward the right in Figure 1 but showing the guard casings employed for the gearing in position;

Figure 3 is a diagrammatic view illustrating 45 how the car puller is utilized to pull a car;

Figure 4 is a view in section taken on line 4-4 of Figure 1, parts being shown in elevation and parts being broken away for the sake of simplicity in illustration;

Figure 5 is a view in elevation showing

the counter shaft and the clutch controlled gears thereof;

Figure 6 is a fragmentary detail view taken in section on line 6-6 of Figure 1 and showing the gearing employed for driving the drums forwardly from the counter shaft, parts being omitted and parts being shown in elevation for the sake of simplicity in illustration; and

Figure 7 is a similar view taken on line 6-6 of Figure 1 showing the gearing employed for reversely driving the drums from the counter shaft.

Referring to the drawings, the numeral 1 designates a base or frame on which a pair of drums, designated at 3 and 4, are mounted, the drums 3 and 4 having shafts 5 and 6 rotatably supported in bearings 7 secured to the frame 2. The drums 3 and 4 are provided with peripheral grooves 3' and 4' adapted to receive portions or turns of a cable designated generally at 8. The cable 8 extends in under the drum 3 up, over and around the drum 4 and back up, over and around the drum 3. This wrapping of the cable around the drums 3 and 4 is repeated a number of times so that the drums have sufficient traction or gripping engagement with the cable to drive the same under heavy load.

Beyond the drums the ends of the cable are extended around pulleys 9 and 10 and thence to the axle A of a car C, the ends of the cable being releasably attached to the axle in any suitable way. In pulling the car one way, one end of the cable 8 is hauled in while the other is laid out. An opposite movement of the car requires, of course, a reverse movement of the cable. This cable actuation requires that the drums 3 and 4 be moved in opposite directions and to constrain the drums to so rotate they are provided with twin gears 11 fixed to their respective drums 3 and 4 or to their respective drum shafts 5 and 6 and intermeshing one with the other.

The present invention proposes to drive the drums in either forward or reverse direction and at either high or low speed in either forward or reverse and in carrying

out this purpose a suitable motor designated generally at 15 is secured and bolted to the base 1. The motor 15 may be an electric motor, an internal combustion engine or any other suitable type of power plant. As shown in Figure 1, the motor shaft 16 is coupled as at 17 to a drive shaft 18 which has its intermediate portion rotatably supported in a fixed sleeve shaft 19, the ends 10 of the latter being supported in and suitably secured to bearing brackets 20 (see Figure 4). The portions of the drive shaft 18 which lie outside of the fixed sleeve shaft 19 have driving gears 21 and 22 keyed thereon and 15 constantly meshing with driven gears 23 and 24, respectively (compare Figures 1 and 4). The driven gears 23 and 24 are loosely mounted on a counter shaft 25 rotatably supported in bearings 26 secured to the base of 20 the machine. As illustrated in Figures 1, 4 and 5, the driving gear wheels 21 and 22 are of different diameters and the driven gear wheels 23 and 24 may also be of different diameters so that these gear wheels 25 21, 22, 23 and 24 provide change speed gear mechanism operable to drive the counter shaft 25 from the drive shaft 18 at different speed and power ratios, that is, the gears 21 and 23 provide a low speed drive and 30 the gear wheels 22 and 24 a high speed drive for the counter shaft. As pointed out, the driven gear wheels 23 and 24 are loosely mounted on their counter-shaft 25 but they are selectively clutched or fixed to the counter-shaft by means of friction clutches designated at 27 and 28, the clutches being of well known construction and being thrown in or 35 out by well known clutch operating mechanism designated at 29 and 30, the operating mechanism 29 and 30 for the respective clutches being controlled from shifters 31 and 32 fulcrumed on the base and linked as at 33 and 34 to crank arms 35 and 36 fixed on a control shaft 37 supported for oscillating movement in bearing brackets 39 and 40. When the lever 40 is moved in one direction it engages the clutch 27 and disengages the clutch 28 and upon reverse movement the lever is operable to engage clutch 28 and disengage clutch 27. Between its 45 two extremes of movement the lever 40 has a neutral position in which both clutches 27 and 28 are disengaged.

At either speed of the counter shaft it is proposed to drive the drums 3 and 4 either forwardly or reversely from the counter-shaft and for this purpose a forward driving gear 35 is loosely mounted on the counter shaft but is clutched thereto when desired by means of a friction clutch 36 (compare Figures 1 and 5). The gear 35 constantly meshes with a driven gear wheel 37 fixed to a rotatable sleeve shaft 38 (see Figure 4) fitted on the fixed sleeve shaft 19 for rotation

thereabout. A pinion 39 is also secured to the sleeve shaft adjacent the gear wheel 37 and this pinion 39 meshes with one of the twin gears 11 which, it will be remembered, are connected to the drums to constrain them to proper relative rotation. 70

The drums 3 and 4 are driven forwardly in either high or low speed from the counter-shaft 25, through the gear wheel 35, gear wheel 37, pinion 39, and twin gear 11 of 75 drum 4.

For reversely driving the drums from the counter-shaft in either speed (compare Figures 1 and 7), a gear wheel 40 is loosely mounted on the counter-shaft 25 but is clutched thereto when desired by means of a friction clutch 41. The gear wheel 40 meshes with an intermediate gear 42 rotatably supported on a fixed shaft 43 and meshing with a large gear wheel 44 fixed to the end of the rotatable sleeve shaft 38 opposite the gear wheels 37 thereof. When the clutch 41 is engaged the counter-shaft drives the gear wheel 40 which, in turn drives the intermediate gear 42 and this gear 42 meshing with the gear wheel 44 and turns the sleeve shaft 38 on which the gear wheel 44 is fixed and thereby also rotates the pinion 39 which as previously described meshes with the twin gear 11 of the drum 4. In this way 95 the drums are reversely driven. 90

The clutches 36 and 41 are alternately thrown in and out from a single collar 50 slidably mounted on the counter-shaft 25 in between the clutches 36 and 41 and operatively connected with the operating mechanism for these clutches in the usual manner. The collar 50 is actuated from a single shifter 51 having a form of a bell crank and linked as at 52 to a crank arm 53 fixed to a sleeve shaft 53 rotatably mounted on the control shaft 37 and provided with a hand lever 54. When the control lever 54 is moved in one direction it rocks the sleeve shaft 53 and acts through the link 52 and shifter 51 to slide the collar in one direction to engage the clutch 36 and disengage the clutch 41. The reverse movement of the lever 54 engages the clutch 41 and throws out the clutch 36. The control mechanism insures the disengagement of one of the clutches 36 and 41 when the other is engaged thereby precluding injury to the mechanism. The control lever 54 also has an intermediate position in which both clutches 36 and 41 are disengaged. 115

With the description above described, cars may be shifted along track-ways rapidly and easily and may be effectively spotted, that is, accurately positioned in front of a loading station. The high speed drive for the drums provides for rapid movement of empty cars or even of loaded cars where the going is easy. The low speed-high power ratio makes it possible to move the cars 130 125 130

easily and expeditiously when loaded and to accurately spot them.

The invention claimed is:

1. A car puller of the character described comprising a pair of drums adapted to drive a cable, twin gears constraining the drums to rotate in opposite directions, a motor driven shaft, a counter-shaft, clutch controlled gearing for driving the counter-shaft at variable speed and power ratios from the motor driven shaft, a clutch controlled gear set for driving one of the twin gears of the drum forwardly from the counter-shaft and including a sleeve shaft having a pinion fixed thereto and meshing with one of the twin gears, and clutch controlled gearing for reversely rotating the sleeve shaft from the counter-shaft.
2. A car puller of the character described comprising a drum arrangement adapted to drive a car pulling cable in either direction, a motor driven shaft, a fixed sleeve shaft rotatably supporting an intermediate portion of the motor driven shaft, a counter-shaft, clutch controlled change speed gearing for driving the counter-shaft from the motor shaft at variable speed and power ratios, a rotating sleeve shaft mounted on the fixed sleeve shaft and geared to the drum arrangement, a clutch controlled forward driving gear set interconnecting the counter-shaft and the rotating sleeve shaft and a clutch controlled reversing gear set interposed between the counter-shaft and the rotating sleeve shaft.
3. A car puller of the character described comprising a drum arrangement adapted to drive a car pulling cable in either direction, a motor driven shaft, a fixed sleeve shaft supporting said motor driven shaft, a counter shaft, a high speed gear set for driving the counter-shaft from the motor shaft, a clutch mounted on the counter-shaft controlling the action of the high speed gear set, a low speed gear set for driving the counter-shaft from the motor shaft, a clutch mounted on the counter-shaft and controlling the action of the low speed gear set, a single control lever connected to said clutches for simultaneously engaging one and disengaging the other, forward and reverse driving gear sets between the counter-shaft and the drum arrangement, clutches mounted on the counter-shaft and controlling the operation of the forward and reverse driving gear sets, and a single lever for engaging one of the said last-mentioned clutches and simultaneously disengaging the other.
4. A car puller of the character described comprising a pair of drums adapted to drive a car pulling cable in either direction, twin gears constraining the drums to corresponding rotation, a motor driven shaft, a counter-shaft, change speed gearing for driving the

counter-shaft at variable speed and power ratios from the motor driven shaft, clutches mounted on the counter-shaft and controlling the action of the change speed gearing, a rotatably supported sleeve shaft having 70 a pinion fixed thereto and meshing with one of the twin gears, forward and reverse driving gear sets interconnecting the sleeve shaft with the counter-shaft, and clutches mounted on the counter-shaft for controlling 75 the operation of the forward and reverse driving gear sets.

In witness whereof, I hereto affix my signature.
